UNITED STATES PATENT OFFICE.

WILLIAM NIXON BUTLER, OF PRAIRIE GROVE, ARKANSAS.

LOCK.

1,265,424.

Specification of Letters Patent.

Patented May 7, 1918.

Application filed February 6, 1918. Serial No. 215,568.

To all whom it may concern:

Be it known that I, WILLIAM N. BUTLER, a citizen of the United States, and a resident of Prairie Grove, in the county of Washington and State of Arkansas, have invented 5 a new and Improved Lock, of which the following is a full, clear, and exact description.

My invention relates to mortise locks and rim knob locks, and more particularly to a 10 gravity lock in which the bolt is thrown through the medium of devices actuated by the knob spindle and in which separate key-controlled devices serve to lock or release the bolt for permitting its operation by the knob 15 spindle, the arrangement doing away entirely with springs for controlling the parts thereby avoiding the annoyance of broken or damaged springs.

An object of the invention is to provide 20 in a lock of the indicated character, bolt controlling means improved in various particulars with a view to effect the positive operation of the parts and insure the locking, unlocking, and movement of the bolt.

25 A more specific object is to provide a strong construction involving simple parts.

Reference is to be had to the accompanying drawings forming a part of this specification, in which similar reference characters indicate corresponding parts in all the 30 views, it being understood that the drawings are merely illustrative of one example of the invention.

Figure 1 is a sectional side view of a lock 35 constructed in accordance with my invention, showing the bolt projected and locked;

Fig. 2 is a similar view showing the parts with the bolt unlocked and withdrawn;

Fig. 3 is a horizontal section on the line 40 3—3, Fig. 1;

Fig. 4 is a transverse vertical section on the line 4—4, Fig. 2.

In carrying out my invention in practice, in accordance with the illustrated example, 45 a suitable casing 10 is provided to be mortised in a door A in the usual manner. Within the casing 10 is a slide bolt 11 movable laterally through an opening 12 in the face of the casing between a pair of guide pins 13 on the casing at the interior. In the bolt 11 is a vertical recess 14 to receive the hooked end 15 of one arm of a locking lever 16 which is pivoted between its ends by a pivot 17 to the casing.

50 To the opposite arm of the lever 16 is pivotally hung as at 18 a controlling weight 19

which is formed at its lower edge with recesses 20 to receive a bit b of a key B when the latter is inserted through the keyhole C. The numeral 21 indicates a stop for 60 limiting the upward movement of the locking lever 16. An additional recess 20^a is produced in the lower edge of the pivoted weight 19 adapted in the locking position of the lever 16 to accommodate a pin 22. The 65 numeral 23 indicates fixed wards disposed in the casing 10 at opposite sides of the keyhole C to guard against the throwing of the weight 19 by a key or device other than the proper key.

70 The described devices serve to lock the bolt in the projected position as in Fig. 1. With the bolt withdrawn the locking lever 16 will be maintained by its weight 19 above the rocking bolt 11 and out of engagement 75 therewith. To actuate the bolt 11 from the knob spindle D a rockable weighted controlling lever designated generally by the numeral 24 is provided in the casing 10 and pivoted at the top, at one corner thereof, 80 by any suitable pivot 25. The lower end 26 of the element 24 is weighted as at 26. The connection between the bolt 11 and the controlling weighted element 24 is effected by a slot and pin, there being a vertical slot 27 85 in the bolt 11 at its inner end and a pin 28 on the element 24 extending into said slot. The element 24 is cut away as at 29 to allow clearance for said element in moving relatively to the pivot 17 of the lever 16. On 90 the knob spindle D are lateral elements 30, 31 somewhat on the order of rollbacks, whereby to rock the element 24 on its pivot 25 in opposite directions to withdraw the bolt 11 or project the same, said members 95 30, 31 being here shown as formed on a sleeve 32 on the knob spindle, said sleeve and members having clearance in an opening 33 in the element 24, said opening 33 being complementary to opening 29.

100 With the described construction, assuming the bolt 11 to be in the projected position as in Fig. 1, the key B is inserted and turned to engage the weight 19 in a recess 20 thereof, thereby giving said weight and lever 16 105 a movement to dislodge the weight from the rest pin 22 permitting the weight to drop to the position of Fig. 2, thereby throwing the locking lever 16 out of engagement with the bolt 11. The movement brings the weight 19 110 to a position at a side of the rest pin 22 with the opposite end of the lever 16 against stop

pin 21 so that the locking lever is maintained disengaged from the latch bolt until said lever is again thrown to the locked position by the key. After the release of the latch bolt, the latter may be withdrawn by a turning of the knob spindle D which acts through a member 30 or 31 engaging the weighted controlling element 24, said element in turn acting through the pin 28 to withdraw the latch bolt. The element 30 or 31 will engage the weighted element 24 according to the direction in which the knob spindle is turned and in either case the weight 26 tends to restore the latch bolt to the projected position.

I would state in conclusion that while the illustrated example constitutes a practical embodiment of my invention, I do not limit myself strictly to the mechanical details herein illustrated, since manifestly the same can be considerably varied without departure from the spirit of the invention as defined in the appended claims.

Having thus described my invention, I claim as new, and desire to secure by Letters Patent:

1. In a lock of the class described, a latch bolt, a pivoted weighted element engaging said latch bolt and normally tending to throw the same to the projected position, means to rock said element from the knob spindle of the lock, a locking lever pivoted between its ends and adapted at one end thereof to engage the latch bolt in the projected position of the latter to lock the same against withdrawal, a weight pivotally hung on the opposite arm of the locking lever, said weight being adapted to be engaged by a key inserted in the lock, and means to hold the pivoted weight of the locking lever against gravitational movement to thereby maintain the locked position of the latch bolt.

Copies of this patent may be obtained for five cents each, by addressing the "Commissioner of Patents, Washington, D. C."

2. In a lock of the class described, a latch bolt, a pivoted weighted element having a slot and pin connection with the latch bolt and adapted to be actuated by the knob spindle of the lock to withdraw or project the latch bolt, the latch bolt having a recess therein, a locking lever pivoted between its ends, a hook on one arm of the lever adapted to engage the latch bolt in the recess thereof, a weight pivotally hung on the opposite arm of said lever and having recesses in the under side adapted to receive the bit of a door key, and a fixed rest pin with which the pivoted weight on the locking lever is adapted to be engaged and on which said weight may rest in the locking position of said lever.

3. A lock of the class described including a casing having a keyhole, a knob spindle, a pivoted weighted element adapted to be rocked by the knob spindle and adapted to actuate the latch bolt, said latch bolt having a vertical recess therein, a locking lever pivoted between its ends in the casing, one arm of the lever having a depending hook adapted to enter said recess of the latch bolt, a weight pivotally hung on the opposite arm of the lever and tending to maintain said lever out of engagement with the latch bolt, the lower end of said weight on the locking lever being adapted to be engaged by a key inserted in the lock for throwing the lever to the locking position, means to hold said pivoted weight against gravitational movement to thereby maintain the locking lever in locking position, a fixed pin in the casing in position for said pivoted weight to rest thereon when the lever is in the locking position, and fixed wards in the casing at angles to each other and positioned at opposite sides of the keyhole.

WILLIAM NIXON BUTLER.
